UNITED STATES PATENT OFFICE.

CHARLES HARTER, OF ST. LOUIS, AND ROBERT WARK, OF MAPLEWOOD, MISSOURI.

SLACK-ADJUSTER FOR CAR-BRAKES.

1,192,420.

Specification of Letters Patent.

Patented July 25, 1916.

Application filed November 8, 1915. Serial No. 60,270.

To all whom it may concern:

Be it known that we, CHARLES HARTER and ROBERT WARK, citizens of the United States, residing at St. Louis, Missouri, and 5 Maplewood, Missouri, respectively, have invented a certain new and useful Improvement in Slack-Adjusters for Car-Brakes, of which the following is a full, clear, and exact description, such as will enable others 10 skilled in the art to which it appertains to make and use the same, reference being had to the accompanying drawings, forming part of this specification.

Our invention relates generally to the air 15 brake systems of railway cars and more particularly to a slack adjuster, that is, a device for taking up the slack in power operated brakes so that the travel of the piston in the power cylinder will always be substantially the same, regardless of the wear upon 20 the brake shoes or the lost motion which may develop in the brake rigging.

The principal object of our invention is to provide comparatively simple, inexpensive and effective slack adjusting means which can be readily combined with the 25 brake rigging now in general use upon railway cars, and which adjusting means is adapted to be manually operated from the 30 side of the car when an adjustment is made, thus obviating the necessity for a person making adjustments, to pass between or beneath cars in order to reach the adjustable parts of the device.

We are aware that there are numerous 35 forms of slack adjusters which are automatic or semi-automatic in operation, and further that there are various devices which are capable of adjustment from points between or beneath the car, but in our improved device it is the intention to extend a part of the adjusting means to a point upon or adjacent to the side frame of the truck, or to a point which is readily accessible to an operator positioned at the side 40 of the car.

With the foregoing and other objects in view, our invention consists in certain novel features of construction and arrangement of 45 parts, hereinafter more fully described, claimed, and illustrated in the accompanying drawings, in which—

Figure 1 is a plan view of a portion of a car truck and showing our improved slack

adjuster positioned thereupon and connected 55 to one of the dead levers of the brake rigging. Fig. 2 is an enlarged sectional view taken approximately on the line 2—2 of Fig. 1 and showing a portion of the adjusting means in elevation. Fig. 3 is a vertical section taken approximately on the line 3—3 of Fig. 2. Fig. 4 is a top plan view of a modified form of the slack adjuster. Fig. 5 is a perspective view of one of the parts which serves as a fulcrum for the dead lever. 65 Fig. 6 is a top plan view of a further modified form of the adjusting device. Fig. 7 is an enlarged side elevational view of the modified construction seen in Fig. 6. Fig. 8 is an elevational view looking in the direction indicated by the arrow 8 in Fig. 6.

Referring by numerals to the accompanying drawings, and particularly the form of device illustrated in Figs. 1 to 5 inclusive, 10 designates the truck bolster, 11 the upper arch bar of the truck side frame, 12 the 75 brake beam, and 13 the usual dead lever which is pivotally connected to the brake beam or to a bracket positioned thereupon. Fixed in any suitable manner to the bolster 10 is a plate 14 with which is formed integral a pair of upwardly projecting ears 15, the same being preferably inclined to correspond with the inclination or angular position normally occupied by the dead lever 80 13. Passing through these ears is a pin 16 and pivotally mounted thereupon and positioned between said ears is one end of a horizontally disposed arm 17, the outer end 85 of which is bifurcated to form substantially parallel legs 18. Formed in the lower edges of these legs 18 are notches 19, the same being arranged in pairs. This arm 17 is bent so that the end which is pivotally connected to pin 16 occupies a plane which 90 is slightly higher than that occupied by the parallel legs 18.

Positioned directly over the arm 17 and legs 18 is a member which comprises a pair of substantially parallel legs 20 which lie 100 at the sides of the ears 15 and said legs are provided with longitudinally disposed slots 21 which receive the ends of the pin 16.

Formed integral with the legs 20 is an elongated housing 22 which is substantially 105 of inverted U-shape in cross section and which overlies the parallel legs 18. Formed in the lower portions of the sides of this in-

verted U-shaped member are longitudinally disposed slots 23 and extending upwardly therefrom are notches 24, the same being arranged in pairs and approximately the same depth as the notches 19 in legs 18.

Projecting from the end of the housing 22 adjacent to the point where the same unites with the legs 20 is an ear 25, and pivotally connected thereto is one end of a link 26. The other end of this link is journaled on a wrist-pin or trunnion which projects from the face of a disk 27, the latter being fixed on the inner end of a shaft 28. This shaft extends from the plate 14 to a point slightly beyond the arch bar 11 and is journaled in bearings 29 and 29^a which are formed on said plate and arch bar respectively.

The outer end of shaft 28 is preferably made square or non-circular in order to receive a wrench or like tool which may be utilized in imparting rotary motion to said shaft. When this form of adjusting device is utilized, the fulcrum pin 13^a on the upper end of the dead lever 13 occupies corresponding pairs of the notches 19 and 24 in the legs 18 and member 22. When it becomes necessary to shift the fulcrum of the dead lever to compensate for wear upon the brake shoes or for slack which has developed in the brake rigging, an operator positioned to the side of the car places a wrench or suitable tool on the outer end of shaft 28 and rotates the same one complete turn.

It will be understood that the parts of the adjusting mechanism normally occupy positions as illustrated in Fig. 1 and when shaft 28 is thus rotated, member 22 and legs 20 will be first moved toward the left hand and thence toward the right hand. The legs 20 being slotted permit this reciprocating movement and as said member moves toward the left hand, fulcrum pin 13^a will be moved a distance of one notch during which movement the free ends of legs 18 will be slightly elevated to permit the fulcrum pin to pass the teeth between two of the notches in said legs. As fulcrum pin drops into the next adjacent pair of notches 19, the member 22 completes its movement toward the left hand and during the return movement, or to bring said member and the legs 20 to normal position, the reciprocating member will be elevated slightly to permit the teeth between the notches 24 in the inverted U-shaped member to pass over fulcrum pin 13^a.

When this operation has been accomplished, the fulcrum pin will be located a distance of one notch from the point it previously occupied, and which operation necessarily takes up a certain amount of slack in the brake rigging. This operation can be repeated from time to time as it becomes necessary to take up slack in the brake rigging and said operation can be ac-

complished with perfect safety by the operator, by reason of the fact that said operator is not obliged to pass between or beneath the cars to effect the necessary adjustments.

In the modified construction illustrated in Fig. 4, the legs 20 are extended to form ears 20^a to which the link 26 is pivotally connected. Necessarily this construction shifts the position of the shaft 28 from one side 75 of the bolster to the other.

In the modified construction illustrated in Figs. 6 to 8 inclusive, the upper end of the dead lever is connected to one end of a chain 30 which passes around a grooved pulley 31 80 located at the outer end of a slotted bracket 32. This bracket is fixed to the bolster and serves as a guide for the upper end of the dead lever. From said pulley 31 the chain passes around a second pulley 33, the same 85 being journaled on the base of bracket 32 and from this last mentioned pulley the chain is extended outward through a cross-shaped opening 34, the same being formed in a bracket 35 which is fixed in any suitable 90 manner to the upper arch bar of the truck side frame. Normally, the outer end of the chain occupies the lower end of the cross-shaped opening 34 as illustrated in Figs. 7 and 8 with one of the links of said chain 95 arranged cross-wise of said opening. To take up slack with this form of device, it is only necessary to elevate the free end of the chain to bring the same into the upper portion of the cross-shaped opening and to pull 100 said chain outward a distance of one or more links. This operation necessarily shifts the fulcrum point of the dead lever and takes up whatever slack which may have developed in the brake rigging.

A slack adjuster of our improved construction is comparatively simple, can be readily applied to the various forms of brake rigging now in general use, is positive and effective in operation, and can be manipulated from a point alongside the car or truck to which it is applied.

In practice, we do not intend to confine ourselves to the details of construction herein illustrated and described, as the various parts of the device can be modified, without departing from the spirit and principle of our invention, the scope of which is set forth in the appended claims.

We claim:

1. In a slack adjuster for railway brakes, the combination with a car truck and the brake rigging associated therewith, which rigging includes a dead lever, of means mounted on the bolster of the truck for shifting the fulcrum of said dead lever, a portion of which extends to the side 115 of said car truck.

2. In a slack adjuster for railway brakes, the combination with a truck and the brake 120

rigging associated therewith, which rigging includes a dead lever, of means mounted on the bolster of the truck and connected to said dead lever for shifting the position of the 5 fulcrum thereof, and means extending to the side of the car truck for actuating said fulcrum shifting means.

3. In a slack adjuster for railway brakes, the combination with a truck and the brake 10 rigging associated therewith, which latter includes a dead lever, of a guide for the upper end of the dead lever which guide is mounted upon the truck bolster, and means associated with said guide for shifting the 15 fulcrum of said lever, which shifting means is operable from the side of the car truck.

4. In a slack adjuster for railway car 20 brakes, the combination with a truck and the brake rigging associated therewith, which latter includes a dead lever, of manually operated means mounted on the truck bolster and side frame for shifting the position of the fulcrum of said dead lever.

5. In a slack adjuster for railway car 25 brakes, the combination with a truck and the brake rigging associated therewith, which latter includes a dead lever, of adjusting means mounted on the bolster of the truck for engaging the upper end of the dead lever, and manually operable means extending to the side of the truck frame for actuating the first mentioned means.

6. In a slack adjuster for railway car 35 brakes, the combination with a truck and the brake rigging associated therewith, which latter includes a dead lever, of a member supported by the truck bolster and provided with notches which are adapted to receive the fulcrum pin of the dead lever, and manually operable means extending to the side of the truck frame for shifting the position of said notched member.

7. In a slack adjuster for railway car 45 brakes, the combination with a truck and the brake rigging associated therewith, which latter includes a dead lever, of a pair of members provided with notches which are adapted to receive the fulcrum pin of the dead lever, and manually operable 50 means extending to the side of the truck frame for actuating one of said members.

8. In a slack adjuster for railway car 55 brakes, the combination with a truck and the brake rigging associated therewith, which latter includes a dead lever, of manually operable means supported by the truck bolster and the truck side frame for adjust-

ing the normal angular position of the dead lever.

9. In a slack adjuster for railway car 60 brakes, the combination with a truck and the brake rigging associated therewith, which latter includes a dead lever, of a manually operable flexible connection between the dead lever and the side of the truck frame for adjusting the fulcrum of said 65 dead lever which flexible connection is supported by the truck bolster and truck side frame.

10. The combination with a railway car 70 truck and the brake rigging associated therewith, of means supported by the truck bolster and manually operable from the side of said truck for taking up the slack in said rigging.

11. In a slack adjuster for railway car 75 brakes, a pair of notched members adapted to coöperate and form a bearing for the fulcrum pin of the dead lever of said brake rigging.

12. In a slack adjuster for railway car 80 brakes, a pair of notched members adapted to coöperate and form a bearing for the fulcrum pin of the dead lever of said brake rigging, and means extending to the side of the car truck for actuating one of said members 85 to shift the fulcrum pin of the dead lever.

13. The combination with a car truck and the brake rigging associated therewith, of a notched member supported by the bolster of the truck and adapted to serve as a bearing 90 for the fulcrum pin of the dead lever of said rigging, and means for manually operating said member from the side of the car.

14. In a slack adjuster for railway car 95 brakes, the combination with a truck and the brake rigging associated therewith, which latter includes a dead lever, a member supported by the truck bolster and forming a fulcrum for said dead lever, a shaft 100 supported by the truck bolster and extending to the side of the truck, and connections from said shaft to the fulcrum member whereby the position of the latter is shifted when said shaft is rotated.

In testimony whereof we hereunto affix our signatures in the presence of two witnesses, this 6th day of November, 1915.
